US00D911173S

(12) **United States Design Patent** (10) Patent No.: **US D911,173 S**
(45) Date of Patent: ** *Feb. 23, 2021

(54) **DISPENSING BOTTLE CAP**

- (71) Applicant: **Chubby Gorilla, Inc.**, Santa Fe Springs, CA (US)
- (72) Inventor: **Eyad Aboabdo**, Fullerton, CA (US)
- (73) Assignee: **Chubby Gorilla, Inc.**, Fullerton, CA (US)
- (*) Notice: This patent is subject to a terminal disclaimer.
- (**) Term: **15 Years**

(21) Appl. No.: **29/689,595**

(22) Filed: **Apr. 30, 2019**

Related U.S. Application Data

- (63) Continuation of application No. 29/655,619, filed on Jul. 5, 2018, now Pat. No. Des. 860,004, which is a continuation of application No. 29/573,527, filed on Aug. 6, 2016, now Pat. No. Des. 834,950, and a continuation of application No. 29/655,623, filed on Jul. 5, 2018, now Pat. No. Des. 855,476, which is a continuation of application No. 29/573,527.

CLAIM

The ornamental design for a dispensing bottle cap, as shown and described.

DESCRIPTION

FIG. 1 is a perspective view of a dispensing bottle cap showing my new design;

FIG. 2 is an elevation view thereof.

FIG. 3 is a top plan view thereof; and,

FIG. 4 is a bottom plan view thereof.

The broken lines showing a bottle depict environmental subject matter that forms no part of the claimed design.

1 Claim, 2 Drawing Sheets
